HIGH VOLTAGE GROUNDING RELAY

Jack S. Hawkins and Larry G. McClary, San Jose, Calif.,
assignors to Jennings Radio Manufacturing Corpora-
tion, San Jose, Calif., a corporation of Delaware

Filed Dec. 26, 1962, Ser. No. 72,959

Term of patent 14 years

(Cl. D26—13)

FIG. 1 is a side elevation of the high voltage grounding relay.

FIG. 2 is a plan view; and

FIG. 3 is a bottom view of the relay.

The characteristic features of the design reside in elongated insulation portion having a rounded top portion, an intermediate portion of frustro conical shape at the top of the bottom larger diameter portion, uniform spacing between the ribs and the upper smaller diameter portion being longer than the lower larger diameter portion.

We claim:

The ornamental design for a high voltage grounding relay, as described and shown.
